(57) **CLAIM**

I claim the ornamental design for an undergarment, as shown and described.

DESCRIPTION

FIG. 1 is a front perspective view of an undergarment.

FIG. 2 is a front elevation view of the undergarment shown in FIG. 1.

FIG. 3 is a rear elevation view of the undergarment shown in FIG. 1.

FIG. 4 is a left side elevation view of the undergarment shown in FIG. 1.

FIG. 5 is a right side elevation view of the undergarment shown in FIG. 1.

FIG. 6 is a front perspective view of a second embodiment of the undergarment shown in FIGS. 1-5;

FIG. 7 is a front elevation view of the undergarment shown in FIG. 6.

FIG. 8 is a rear elevation view of the undergarment shown in FIG. 6.

FIG. 9 is a left side elevation view of the undergarment shown in FIG. 6; and,

FIG. 10 is a right side elevation view of the undergarment shown in FIG. 6.

Any showing of the environment by broken lines having equal length segments is for illustrative purposes only and forms no part of the claimed design. The portions of the undergarment shown in broken lines having unequal length segments illustrate the boundary of the claimed design and form no part of the claimed design. FIGS. 6-10 show contrast in materials by using line shading in one area and stippling in another.
